UNITED STATES PATENT OFFICE.

HENRY M. GREEN, OF LOS ANGELES, CALIFORNIA, ASSIGNOR TO EARL P. HOPKINS,
OF COUNCIL BLUFFS, IOWA.

PUMP.

Application filed December 1, 1922. Serial No. 604,337.

To all whom it may concern:

Be it known that I, HENRY M. GREEN, a citizen of the United States, residing at Los Angeles, in the county of Los Angeles 5 and State of California, have invented new and useful Improvements in Pumps, of which the following is a specification.

This invention relates to deep well plunger pumps, and has for an object to provide an 10 improved form of packing and plunger. Another object is to provide means for automatically expanding the deformable packing and which expansion is secured by the action of the load superimposed on the lifting stroke of the plunger. Another object 15 is to provide an improved packing swab.

A further object of the invention is to provide in a pump in which there is a tight 20 fitting, reciprocating plunger means for bypassing the load above the plunger to discharge accumulated sand and liquid upon occasions of necessity.

Another object is to provide a pump plunger with one or more deformable and 25 expansible packing swabs and means operative automatically to lock the compressed and expanded packing swabs.

Other objects and advantages will be made 30 manifest in the following specification of embodiments of the invention illustrated in the accompanying drawings, wherein

Figure 1 is a central longitudinal section of a form of the invention.

Fig. 2 is a central longitudinal section 35 showing the swab plunger in elevation and in sand or pump discharging position with respect to by-pass means.

Fig. 3 is a longitudinal central section and 40 partial elevation of the pump.

Fig. 4 is a perspective of a swab device before introduction into the pump plunger.

Fig. 5 is a cross section through the swab 45 showing the carrying ring.

Fig. 6 is a central longitudinal section 50 showing in detail the automatic swab lock.

Fig. 7 is a plan of the lock jaws and cross section of the plunger tube.

Fig. 8 is a side elevation and sectional 55 view of one of the swab expanding cups.

Fig. 9 is a side elevation and partial section of a modified form of swab cup.

Fig. 10 is a central longitudinal section of 60 the improved pump showing the utilization of the modified form of swab cup.

The improved pump is of the type usu-

ally employing an external cylindrical jacket 2, the upper end of which is screwed into a pipe joint or fitting 3 to which is secured the lower end of the usual pump pipe 4 through which reciprocates the usual 60 polish or sucker rod. The lower end of the pump jacket 2 is connected to a foot joint 6 to which may be connected the usual inlet suction or perforated sleeve 7 leading down into the well. The joint 6 also forms a seat 6^a for the standing valve of the pump, and this is shown as including a ball 8 arranged in a cage 9 and which is provided with a bushing 10 to close down on the seat 6^a. The cage 9 is suitably connected to a 65 garbutt rod 11 sliding through a guide plug 12 forming the lower end of a plunger which includes a plunger tube 13 of suitable length and may be of sectional or unitary construction as desired.

The plunger tube 13 is here shown as connected at its upper end to a collar 14 to which is attached an upwardly extending tubular section 15 of the plunger, this in turn being connected to the upper valve 16 70 and which upper valve is connected to the sucker rod 5.

The connecting collar or guide 14 has a 75 free sliding fit in a working barrel 18, the upper end of which is mounted in the upper coupling or collar 3, and the lower end of which is shown as secured at 19 in the lower joint or shoe 6.

A feature of the invention resides in the 80 construction of the plunger and in the packing thereof in the working barrel 18 so as to secure an efficient and tight but running fit of packing means. Means are provided also for automatically compressing and expanding the packing means during the operation of the pump to insure a tight working fit.

The pump plunger and its packing, therefore, consists of one or more swab-like packing devices, each of which, as clearly 85 shown in Figs. 4 and 5, consists of a number of pieces of suitable packing material 20, one end of each of which pieces is suitably connected, as for instance each of the pieces being threaded upon a split wire ring 21.

Thus a number of the packing pieces 20 when threaded upon the ring 21 form a substantially cylindrical hollow swab, and one or more of these is adapted to be arranged along and surround the plunger tube 13. In the construction shown, the connected 90 95 100 105 110

ends of the swab pieces are arranged in a socket or cup 22, and each cup is provided with a body portion 23 fitting over the plunger tube 13. In the assembly of the 5 plunger, one of the cups 22 with its body portion and an inserted swab is secured to the lower end of the plunger tube as by threads 23^a, and this is then followed by another cup and with an inserted swab and 10 so on until a suitable number of the swabs and cups have been applied to the plunger, as is shown in Fig. 1.

To effect the automatic expansion of the 15 swab-like packing device against the working barrel 18, the lower end face of the cup body is shown as beveled as at 23^b, the bevel face converging inwardly and downwardly toward the surface of the plunger tube 13 so that under load the expanding faces 23^b of 20 the series of cups will serve to compress the swab devices and press the same outwardly against the contiguous surface of the working barrel and also inwardly against the adjacent surface of the plunger tube 13.

25 It is desirable to provide for a positive downward sliding action of the swab devices along with the plunger tube 13, and to obtain a firm interlock between the surface of the tube and the swabs, the outer surface of 30 the tube is shown as toothed at 13^a for any suitable distance along its length, these teeth firmly embedding in the compressed swab material during action of the plunger.

To prevent the loosening and loss of the 35 packing efficiency of the swabs, I prefer to employ means for automatically locking the compressed swabs, and such means is clearly shown in Fig. 6 as including an expander body 25 having a conical face 25^a, and on the 40 upper end of this expander body is arranged a series of contractile segmental jaws 26 having inwardly projecting tooth-like portions 26^a to engage with the teeth 13^a of the plunger tube. The contractile jaws 26 are 45 normally under the contractile action of a spring 27 surrounding the same. The jaws and the spring are preferably encased in a thimble 28 mounted on the expander body 25. It will be seen, therefore, that during 50 the action of the plunger, the wear of the packing material and its subsequent shortening is compensated and the tight fit of the packing is maintained by the automatic advancing movement of the follower-like locking jaws 26 which are disposed in a position above the uppermost of the packing swabs.

During operation of the plunger on its 55 downward stroke, oil will pass into the plunger tube 13 through a perforated lower section 13^b thereof and will ascend through the tube and eventually pass above the upper valve 16.

A slightly modified form of the swab cup 60 is shown in Figs. 9 and 10 wherein a double

ended cup is shown as including an intermediate body or ring 23^b from which extends cup portions 22 at each end, and into these cup portions are adapted to be arranged the contiguous ends of the swab devices 20. 70 In this form of swab holder, the ends of the interposed swabs are encompassed in the cup portions 22 and the intermediate portion of each swab is adapted to be expanded and thrust out against the working barrel under 75 compression between the sliding cups which receive the load superimposed by the column of oil or liquid being lifted by the plunger.

An important feature of the invention 80 consists of means for de-sanding and for discharging oil from above the plunger in such instance as may be necessary. To that end the working barrel 18 is shown as provided with an upper series of apertures 18^a and a lower series of apertures 18^b, these 85 series being spaced apart a distance somewhat greater than the length of the effective packing portion of the plunger. Therefore, if an undesirable amount of sand accumulates in the pump, the plunger can be lifted 90 by its sucker rod 5 until the garbutt rod 11 is engaged by the guide lug 12 in the lower end of the plunger, whereupon further upward movement of the plunger results in lifting the standing valve bushing 10 from 95 its seat 6^a. In such an arrangement of the parts, the column of oil and sand collected above the plunger will immediately tend to descend through the ports 18^a and will flow 100 down between the working barrel 18 and the pump jacket 2 and will pass into the working barrel through the ports 18^b and thence past the lifted or unseated foot valve.

It will be seen, therefore, that it is possible 105 by my invention to readily de-sand a pump at any time without entirely removing or pulling the plunger and its polish rod or sucker rod from the casing.

It will be seen that I have provided a 110 plunger pump having an inner tube with a toothed or roughened surface along which there is slidably a compressible packing material adapted to conform with an interlock on the roughened surface of the tube to hold the packing against reverse slipping, but permitting it to be advanced downwardly under the pressure of the superimposed load on the pump plunger in the pump pipe. Also mounted on the toothed 115 plunger tube is a mechanical locking device to engage the teeth on the tube and further to hold the packing against reverse 120 movement.

Further embodiments, modifications and 125 changes may be resorted to within the spirit of the invention as here claimed.

What is claimed is:

1. In a plunger pump, a plunger tube, a cylindrical packing medium surrounding the tube, a retainer for one end of the pack- 130

- ing medium, and an expanding means operative against the opposite end of the packing medium whereby to compress the packing medium between the plunger tube and the 5 working barrel, said packing medium consisting of a swab-like group of longitudinal packing pieces.
2. In a plunger pump, a plunger tube, a cylindrical packing medium surrounding 10 the tube, a retainer for one end of the packing medium, and an expanding means operative against the opposite end of the packing medium whereby to compress the packing medium between the plunger tube and 15 the working barrel, said packing medium consisting of a swab-like group of longitudinal packing pieces, the plunger tube being provided with teeth on its exterior face to interlock with the packing medium.
- 20 3. In a plunger pump, a plunger tube, a cylindrical packing medium surrounding the tube, a retainer for one end of the packing medium, an expanding means operative against the opposite end of the packing 25 medium whereby to compress the packing medium between the plunger tube and the working barrel, said packing medium consisting of a swab-like group of longitudinal packing pieces, and an automatic locking 30 means slidable along the plunger tube for maintaining the packing medium in a compressed condition.
4. In a plunger pump, a plunger tube, a cylindrical packing medium surrounding 35 the tube, a retainer for one end of the packing medium, and expanding means operative against the opposite end of the packing medium whereby to compress the packing medium between the plunger tube and the 40 working barrel, said packing medium consisting of a swab-like group of longitudinal packing pieces, and an automatic locking means slidable along the plunger tube for maintaining the packing medium in a compressed condition, the plunger tube having a 45 toothed exterior surface engageable by the locking means to prevent reverse movement of the packing medium and said means.
5. In a plunger pump, a plunger tube, two 50 annular swabs surrounding the tube, and a cup-like member in which one end of one annular swab is enclosed, said cup-like member having a wedge face operative to expand a contiguous end of the other swab.
6. In a plunger pump, a tubular plunger, 55 and a cup member slidable along said plunger and provided with an annual swab surrounding the plunger tube, said swab consisting of longitudinal pieces of packing material to lie along said tube.
7. A packing swab for plunger pumps, 60 said swab consisting of a cylindrical group of parallel pieces of packing material, and means connecting the pieces at one end of the group.
8. A packing swab for plunger pumps, 65 said swab consisting of a cylindrical group of parallel pieces of packing material, and means connecting the pieces at one end of the group, said means including an element 70 upon which the pieces are threaded.
9. In a plunger pump, a plunger tube having a roughened exterior surface, cylindrical packing means surrounding the tube and which packing is adapted to be compressed by the superimposed load on the plunger so as to interlock upon the roughened surface on the tube.
10. In a plunger pump, a plunger tube having a roughened exterior surface, cylindrical packing means surrounding the tube and which packing is adapted to be compressed by the superimposed load on the plunger so as to interlock upon the roughened surface of the tube, and a mechanical 85 locking device following the said packing and also adapted to interlock on the roughened surface of the tube.

In testimony whereof I have signed my name to this specification.

HENRY M. GREEN.
